MOTOR-DRIVEN HEDGE TRIMMER

James M. Katzfey, Willow Grove, and Donald Joseph Hutt, Philadelphia, Pa., assignors to H. K. Porter Company, Inc., a corporation of Delaware

Application June 18, 1958, Serial No. 51,418

Term of patent 14 years

(Cl. D40—1)

FIG.1.

FIG.3.

FIG.4.

FIG. 2.

Fig. 1 is a view in perspective of a motor-driven hedge-trimmer showing our new design;

Fig. 2 is a fragmentary view in perspective taken from the top and blade end;

Fig. 3 is an enlarged fragmentary side elevational view thereof; and

Fig. 4 is an enlarged end elevational view thereof taken from the handle end.

The blade element is shown broken away in Figs. 2 and 3 for convenience of illustration only.

We claim:

The ornamental design for a motor-driven hedge trimmer, substantially as shown and described.
